(57) **ABSTRACT**

First and second handles 18 and 20 extend from first and second plier parts 24 and 26 with a tool shaft 14 disposed on the handle 20 and extending outward of a pivot at 34 and stows into the outer side of the handle 20. The base 42 of the tool shaft 14 has a mating profile 80 which engages a complimentary mating profile 48 disposed on the pivot at 32 or at a complimentary mating profile 48 in an accessory tool 50. The tool shaft 14 is locked in place by closing the two handles 18 and 20 and engaging the handle locking mechanism 30, and extends from a center of the two handles 18 and 20 when closed.

MULTITOOL WITH LOCKING MULTIPURPOSE DRIVER

CROSS-REFERENCE TO RELATED APPLICATIONS

This application claims the benefit of U.S. Provisional Application Ser. No. 63/364,695 entitled "MULTITOOL WITH LOCKING MULTIPURPOSE DRIVER" filed on 30 Nov. 2021, the contents of which are incorporated herein by reference in its entirety.

BACKGROUND OF THE INVENTION

Multitools are well known devices that have several tool functions included in a single device. Many multitools are designed to be folded up with pliers in the middle as one end of a pair handles, and additional tool functions disposed on features folded into the handles of the pliers. Several examples are shown in U.S. Pat. No. 9,225,153 to Anderson et al., which teaches a multi-function wire stripping hand tool, and includes descriptions of the prior art. U.S. Pat. No. 6,119,561 to Anderson et al. similarly shows multitools including an embodiment which has a shaft and bits, pliers and handles. These devices include screwdriver shafts and tool bits of various kinds and sizes. Unfortunately, the screwdriver shaft may move or even close unintentionally while in use. Additionally, the shaft and bits are not centered with respect to the intended axis of rotation, which makes using them awkward and inefficient.

Restraining the movement of the various tool features of a multitool to keep them in position are also known. U.S. Patent Application No. 2007/0131069 to Rivera et al. and published on 14 Jun. 2007 teaches a folding multipurpose hand tool including a pivoted latch that engages side walls of a handle and a base of a folding tool member to hold the folding tool member in a selected position. A safety interlock latch is provided which keeps a folding blade stowed in a handle when another tool is moved from a first position with respect to the handle. This invention keeps the knife in place (closed) so that it does not open while another tool is being used.

Pins or cutouts have been used to help secure components of a multitool in place during use. U.S. Pat. No. 6,983,506 to Brown on 10 Jan. 2006 teaches a universal, interchangeable tool attachment system, including a snap clip which is used to connect system components by rotating into a pin and secured thereby. The Japanese Patent No. JP2020124803A teaches a tool locking mechanism on a similar multitool which has a tool locking position and tab/notch

Tool bits and tool bit holders/blocks have been incorporated into multitools to hold tool bits. US Patent Application No. 2002/0178875 to Lin and published on 5 Dec. 2002 teaches a combination wrench hammer set which includes a tool bit block and may be part of a multitool.

A multipurpose tool with tool bit holder and blade lock is described in U.S. Pat. No. 7,634,956 to Rivera et al. which teaches a tool bit holder to place multiple tools which fits into the tool. The blade lock incorporates a lever and bar which mates with a notch in the base of the tool accessory to hold the tool accessory when it is extended and to prevent other accessories from opening at the same time as a knife, for example. U.S. Pat. No. 7,347,128 also to Rivera et al. teaches a similar multipurpose tool with a tool bit holder and blade lock. The tool is designed to both lock the tool accessory in place when extended and to prevent an accessory from being extended when another accessory is extended. U.S. Pat. No. 7,185,569 to Knight et al. also teaches a multipurpose folding tool that has a tool bit holder and a similarly functioning blade lock.

Some multitools may close unintentionally or have the screwdriver tool pivot while in use. Additionally, the handle may become open during use exposing the user's hands to be pinched by the handles or jabbed by a dislodged feature of the multitool. Furthermore, many of the accessories on the multitool, such as a screwdriver, extend from one of the handles requiring uneven rotation of the tool to use the screwdriver or similar tool that uses rotation.

SUMMARY OF THE INVENTION

The present invention relates to a multitool **12** with pliers which has two handles **18** and **20** and a plier head **22**, in which at least one handle **20** has a driver component bit **16** and tool shaft **14** pivotably attached to the end of the handle **20** at **34**. The tool shaft **14** receives a tool bit **16** on one end and a driver component base **42** at the other end. The driver component base **42** has a protrusion (tooth/tab) **80** disposed at the end of the tool shaft which interlocks with a space formed by the second end **34** of the handle pivot and the first end of one of the plier head **22** halves **24** and **26** when the tool shaft **14** is in an open position with the handles **18** and **20** in a closed position, or with the indentation (notch/slot) **48** in the base of another accessory tool **50** pivotably attached at **32** to the opposing handle **18**. The tool shaft **14**, base **42**, and driver component bit **16** may be one integral component or may be composed of two distinct components.

A least one handle **20** has a driver component, the tool shaft **14**, attached to the pivot point **34** at the second end of the handle **20**. The driver component **14** has a protrusion (tooth/tab) at its base **42**, **80** which mates with an interlocking indentation (notch/slot) **48** in the opposing handle **18**. The interlocking indentation (notch/slot) **48** may be provided in a complimentary profile base **48** of another tool **50** pivotable attached to the opposing handle **18**.

In alternative embodiments of the present invention the driver component base **42** may be provided with a curved base or mating profile **42**, **80** and **82**, which closely matches the curve or complementary mating profile **48** of the base(s) of tool(s) **50** disposed in the opposing handle **18**. By meshing these curves, a secondary position of engagement approximately 90 degrees from the primary position may be achieved.

In another embodiment, the driver component base **42** may be provided with two protrusions (teeth/tabs) **80** and **82**, the first of which holds the driver component tip **16** and tool shaft **14** along the same plane line as the handle **18** and **20** along the intended axis of rotation, and the second of which holds the tool shaft **14** at an angle nearly perpendicular to the line of the hand for added torque or access. It should be understood that, as used herein, the different mating profiles

including protrusion (tooth/tab) and indentation (notch/slot) may be reversed, or combinations thereof. More than two positions may be utilized.

A handle locking mechanism **30** may be provided to hold the two handles **18** and **20** together preventing the unintentional opening of the handles **18** and **20** from the closed position. A crossmember part or bar **52** of the handle locking mechanism **30** may interact with the tool shaft **14** during deployment, so that the locking mechanism **30** is carried 180 degrees or so for free as it were, requiring only 90 degrees more rotation to engage. The locking mechanism **30** captures the extended shoulders of the fastener at **32** on the opposing handle **18** and renders the entire multitool **12** locked in this configuration.

Yet another embodiment, A plier head **22** and two handles **18** and **20**, one handle **20** has a pivotably attached driver component base **42** and shaft **14** with a protrusion **80** or shape which interlocks with a space adjacent to the plier head **48** at **32** or indentation **48** provided in the base of another tool **50** pivotably attached to the opposing handle **18**, or with the locking mechanism thereof. A tool shaft **14** accepts the stub/notch of the driver component base **42** and a tool bit **16** at the opposite end. The base **42** of the driver component shaft **14** may closely match the tools **50** in the opposite handle **18**, so that the driver component shaft **14** can be fixed at **180** or roughly 90 degrees from stowed position. A pivotably attached locking mechanism **30** holds the two handles **18** and **20** together. A bit storage holder **54** accepts and captures the ball detent **58** of an industry standard $\frac{1}{4}$ " double sided hex insert bit **16**. The plier head **22** is stored chiefly within the recess of one handle **18** when closed. The mating part of a ball detent **58** and the ball detent **58** have the same number designation.

Additional advantages of the present invention include that it is a small hand multitool **12** with multiple functions conveniently disposed upon one tool **12**. The multitool **12** contains a driver component base **42** and tool shaft **14** that accepts industry standard double sided tool bits **16** with ball detents **58** so that they may be easily interchanged. The driver component and tool shaft **14** is stowable (closed position), such that in the closed position, does not pose an injury risk as more traditional screw drivers and the like might when not in use. Stated advantages may be disposed on multitools **12** with various handle **18** and **20** configurations, wherein the minor tools **50** in the opposing handle **18** may be accessed by pivoting them toward the centerline of the closed tool **12**, or accessed by pivoting them away from the centerline of the closed tool **12**.

The driver component base **42** and tool shaft **14** may be separable into two distinct components. A driver component base **42** with a square male stub and a tool shaft **14** which accepts the male stub at one end and an industry standard tool bit **16** at the opposite end. Separable driver component base **42** may accept and turn/drive industry standard square drive sockets. Alternative embodiments of the multitool **12** may also be equipped to provide storage of a secondary double sided tool bit within the tool handle **20** or **18**. The bit storage mechanism **54** may accept a tool bit **16** and capture the ball detent of the bit **16** within a depression or hole **58**. The method of capture may allow the stored bit **16** to pivot about the ball detent at **58**, providing secure storage as well as ease of access and removal.

An advantage of the present invention is that the movement of the shaft **14** is restrained by a locking mechanism(s) **80, 82** to **48** restriction once in position. The base **42** of the driver component shaft **14** may be configured in such a way as to interact with the features disposed in the opposing

handle **18**. The driver component base **42** may interact with features disposed in the opposing handle **18** to limit its motion when in an operable position. The multitool may contain a locking mechanism **80, 82, 48** which secures the two handles **18** and **20** together when the driver component base **42** and tool shaft **14** is engaged, rendering the multitool **12** fixed in this position and limiting the ability of the tool **12** to close or collapse accidentally during use. A secondary operable position approximately 80-90 degrees from the primary operable position may be provided. Such a position would provide additional torque and/or allow better access to driven fasteners during use. A blade lock incorporates a lever **36** and bar **52** which mates with a notch **48** in the base of the tool accessory **50** to hold the tool accessory **50** when the handles **18** and **20** are closed in the plier stow position.

The locking mechanism **30** secures the two handles **18** and **20** together when the driver component and tool shaft **14** is engaged, rendering the tool **12** fixed in this position and limiting the ability of the tool **12** to close or collapse accidentally during use. This locking mechanism **30** may be partially deployed when rotating a tool accessory, such as a tool shaft **14** or screwdriver **14**. It is an advantage of the present invention that movement of the tool shaft **14** is restricted so accidental closing cannot occur. Another advantage of the present invention is that the entire tool **12** can be rendered fixed/rigid.

An advantage of the present invention is that the shaft **14** is centered with respect to the intended axis of rotation. The driver component base **42** and tool shaft **14** may be deployed/engaged so that the installed tool bit **16** is centered with respect to the intended axis of rotation, making it more efficient to use the tool **12** and rendering the tool **12** more like a traditional turning/driving tool (screwdriver) than has been possible previously with tools **12** of this type. An added advantage of the present invention is that the tool bit **16** is rendered centered with respect of the intended axis of rotation without having to remove and replace components.

In another alternative embodiment, two protrusions **80, 82** may be disposed on the driver component base **42**, the first of which holds the driver component base **42** and tool shaft **14** along the same plane/line as the handle **18** and **20** and intended axis of rotation, and the second of which holds the tool shaft at an angle nearly perpendicular to the line of the handle **18** and **20** for added torque or access, providing two positions in which the tool shaft **14** may be angled.

Yet another advantage of the present invention is that the driver component base **42**, tool shaft **14**, tool bit **16** and associated locking mechanism **80, 82** may all be deployed and engaged using only one hand since the locking mechanism **42** also has a ridged portion **84** that can be deployed using a thumb or fingernail.

Other aspects of the present invention includes that the handles **18** and **20** are locked into a closed position, the tool can be used to drive various bits and sockets, and the tool **12** provides for securing an additional bit **16** within the handle **18** and **20**.

These and other aspects of the present invention will become readily apparent upon further review of the following drawings and specifications.

BRIEF DESCRIPTION OF DRAWINGS

The novel features of the described embodiments are specifically set forth in the appended claims; however, embodiments relating to the structure and process of making the present invention may best be understood with reference to the following description and accompanying drawings.

FIG. 1 shows a side view of a multitool 12 with locking multipurpose driver shaft 14, with a driver bit 16 engaged in the driver shaft 14, in which the driver shaft 14 extends from closed and locked handles 18 and 20.

FIGS. 2A-2C show side views of an alternative embodiment of a multitool 12 that can be reduced in size to form a miniature multitool 12, with FIGS. 2A and 2B showing the internal components outlined in dashed lines, while FIG. 2C shows a side view without the internal dashed lines.

FIG. 3 shows a side view of a multitool 12 with locking multipurpose driver 14 according to an embodiment of the present invention with the internal components outlined.

FIG. 4 shows an outer side view of the embodiment depicted in FIG. 3.

FIG. 5 shows a side view of the embodiment depicted in FIG. 3 with the pliers 22 in the open position.

FIG. 6 is a side view of the embodiment depicted in FIG. 3 in which the accessory tool 50 is extended and the handles 18 and 20 are in the closed position.

FIGS. 7A and 7B show side views of a multitool 12 depicting an alternative embodiment of the present invention which has more than one accessory tool 50 each of which has the same complimentary mating profiles 48 with FIG. 7B shows the internal position of the tool parts when stowed.

FIG. 8 shows the multitool 12 of FIGS. 7A and 7B with the tool shaft 14 fully extended and profile 48 mated with the complimentary profile 48 of a tool accessory 50 with the handle lock mechanism 30 partially deployed.

FIGS. 9A-9C show another alternative embodiment of a multitool 12 showing an alternative mating profile 80 (fully extended position) and 82 (angle position) on the base 42 with FIG. 9B depicting the tool shaft at an angle so the handle can be used for added torque and FIG. 9C depicting to tool shaft in the fully extended position.

FIGS. 10A-10E depict various views of the handles 18 and 20 from the edges and the top with FIG. 10A showing the handle 20 with the tool shaft 14 and bit 16 stowed with the handle lock 30 fully open in the stowed position, FIG. B shows the accessory tool 50 lock 36 and rivet 40 with the bar 52 that engages the complimentary mating profile 48 when a tool 50 is extended, FIG. 10C shows an end without handle lock 30, FIG. 10D shows the end with the tool shaft 14 deployed, and FIG. 10 E shows the end with the tool shaft 14 stowed and the handle lock 30 in the open position.

FIG. 11 shows an edge view of an embodiment of a multitool 12 according to the present invention in which more than one tool 50 is stowed in the handle 18 and showing the tool shaft 14 stowed.

FIG. 12 is an exploded view showing the tool shaft 14 with the base 42 and bit 16 with the complimentary mating 48 of a tool accessory 50.

FIG. 13A-13D show side views of an alternative embodiment of a multitool 12 of the present invention showing differing position of the handle locking mechanism 30 going from the stowed position in FIG. 13A, to partially deployed positions in FIGS. 13 B and 13C, to all the way deployed and locked at pivot 32.

FIG. 14 shows a side view of a multitool 12 according to alternative embodiments of the present design depicting the parts in open display.

FIGS. 15A-15C show alternative accessory tools 50 with complimentary mating profiles

48.

FIG. 16A-16F show an alternative view of a tool shaft base 42 which an alternative profile from different angles and demonstrating the interaction with the complimentary mating profile 48 of tool accessory 50.

FIGS. 17A-17E show alternative profiles of a tool shaft 14 used, with square (FIGS. 17B and 17C) and hexagonal (FIGS. 17A and 17D) features as shown.

FIGS. 18A-18E depict different perspectives of a bit holder 54 that may be incorporated into a handle (18 or 20) to store additional bits 16 for the tool shaft 14.

FIGS. 19A-19D show the handle locking mechanism 30 from various angles.

FIGS. 20A-20I shows various parts of the multitool 12 of the present invention including the tool shaft 14 (FIG. 20A), tool bit 16 (FIG. 20B), spare tool bit 16 (FIG. 20C), handle lock 30 (FIG. 20D), plier head 22 (FIG. 20E), handles 18 and 20 (FIG. 20F), tool lock lever 36 (FIG. 20G), rivet 40 (FIG. 20H), and tool lock lever spring 56 (FIG. 20I).

FIGS. 21A-21C shows front side and back views of a tool lock lever 36 with a mating bar 52 and a pivot 38.

FIGS. 22A-22C show the operation of the tool lock lever 36 as it operates with a tool 50 that has a complimentary mating profile 48 that can be used to mate with the mating bar 52 of the tool lock lever 36 with the spring 56 and rivet 40 operating to release the tool lock lever 36 and free the tool accessory 50 to be stowed.

FIGS. 23A-23D show details of the handles 18 and 20 of an alternative embodiment of the multitool 12 according to the present invention.

FIG. 24A-24C show an alternative embodiment for the pivots 28, 32, and 34 of the present invention including threaded pin 62, pin shaft 60, threaded pin 62 and pin shaft 60 heads 66 and 68, and spacer sleeve 64 which may be used as a plier stop 44.

FIG. 25 shows another embodiment of the present design with the tool accessory locking mechanism 36 being disposed on the inside of the handle 18 in which the back profile of the bar 52 mates with the tool shaft 14 base 42.

FIGS. 26A and 26B show an alternative configuration of the tool shaft base 42 and angle deployment mating profile 82 which permits the use of the drive shaft 12 fixed at an angle to the handles 18 and 20 and the handle locking mechanism 30 fully engaged in the lock position.

FIGS. 27A and 27B show the alternative configuration of FIGS. 26A and 26B in which the tool shaft 14 is depicted in the fully extended position.

FIG. 28 shows an embodiment of the multitool 12 with a tool accessory lock 36 on the inside of the handle 18 and the alternative design of the tool accessory 50 complimentary mating profile 48 with the tool accessory 50 fully deployed with the handles 18 and 20 in a closed position.

FIGS. 29A and 29B show alternative tool accessories 50 that have the complimentary mating profile 48 for the embodiment of the multitool 12 in which the tool accessory lever lock 36 is on the inside of the handle 18.

FIGS. 30A-30C shows the handles 18 and 20 of the multitool 12 according to the alternative embodiments depicted in FIGS. 25-29B.

FIG. 31 shows an alternative of the tool shaft 12 base 42 which has two positions for mating profile at 80 and 82, and also shows the thumb ridges 84 which facilitate easy opening of the tools, and the ball detent 58 to facilitate mating with a shaft tool 14 that has a ball.

FIG. 32 shows an alternative embodiment of the present invention of a multitool 12 which has additional tools 74 disposed adjacent the plier head 22 at pivots 28.

FIGS. 33A-33D show an alternative configuration of the handles 18 and 20 according to the embodiment of the multitool 12 depicted in FIG. 32 showing where the extra tools 74 are disposed.

FIGS. 34A-34C show alternative threaded pins 62, pin shafts 60, and heads 68.

FIGS. 35A and 35B show alternative mating profiles 80, 82 and complimentary mating profiles 48 that provide for an angled position and an extended position accordingly.

FIGS. 36A-36C show another alternative for the base 42 having a pin 86 and groove 88 configuration which restricts the movement of the tool shaft 14 relative to the handle 20.

FIGS. 37A-37C show an alternative bit holder 54 and detent 58 to receive a bit 16.

DETAILED DESCRIPTION OF THE INVENTION

A side view of an embodiment of a multitool 12 with locking multipurpose driver shaft 14 is shown in FIG. 1. The driver shaft 14 extends from the center of the multitool 12 when the handles 18 and 20 are in a locked closed position with the driver shaft extended. The plier head 22 is not visible in FIG. 1, because it is stowed within the handles in the closed position regardless of whether the driver shaft 14 or other tool 50 is extended from the handle 18 or 20. A latch 30 can be seen in FIG. 1 and is used to lock the handles 18 and 20 together.

At least one tool bit 16 is provided which fits within the tool shaft 14. The tool bit 16 may be two sided. For example, the tool bit 16 may have a Philips head and a flat head disposed on opposing ends of the tool bit 16. A bit storage component holder 54 to retain tool bits 16 therein may be provided for embodiments of the present invention that have more than one tool bit 16. A driver bit 16 is engaged in the driver shaft 14. A tool latch 36 is also shown which pivots at 38 and is released by pushing lever 36. The spring 56 is held in place by the rivet 40. Additional pivots at 28, 32, and 34 provide attachments of tools 50 at 32 and 34, and the driver shaft 14 at 34, to the handles 18 and 20. The plier head 22 plier parts 24 and 26 pivotably attach to the handles 18 and 20 at 28. Additional tool accessories 74 may be attached at 28, as discussed later herein. The driver component 14 with a protrusion (tooth/tab) 80 which interlocks with the space 48 formed by the second end of the handle pivot at 32 and the first end of one of the plier head halves 22 when the tool shaft 14 is in an open position and the handles 18 and 20 are in a closed position.

The tool driver shaft 14 has first and second ends. The tool shaft 14 may have a hexagonal opening at the first end to accept tool bits and a square opening at the second end to accept the male stubs of the driver component. By removing the tool shaft 14 from the driver component base 42, standard 1/4" drive sockets could be fitted to and driving by the driver component base 42.

Another embodiment of the present invention provides for a curved base 42 to the driver component shaft 14. The curve of this base 42 may closely match the curve 48 of the minor tools 50 disposed in the second end 32 of the opposing handle 18. By rotating the driver component base 42 approximately 90 degrees and engaging the locking mechanism 80, 82, 48, the curved base 42 would mesh with the interior implements, and thus be fixed in a position nearly perpendicular to the handles 18 and 20.

In the alternative, each handle 18 and 20 may be comprised of opposing handle parts creating an opening therebetween to permit the plier halves 24 and 26 to be encased therein when the handles 18 and 20 are in a closed position.

Alternatively, the handles 18 and 20 may simply have an alcove sufficient to accommodate the plier halves 24 and 26.

The simplest embodiments depicted in FIGS. 2A-2C could easily use a handle 20 with an alcove to accommodate the tool shaft 14.

FIGS. 2A-2C show side views of an alternative embodiment of a multitool 12 that can be reduced in size to form a miniature multitool 12. FIGS. 2A and 2B shows the internal components outlined in dashed lines. FIG. 2C shows a side view of FIG. 2B without the internal dashed lines demonstrating the central location of the driver shaft 14 when extended from the handles 18 and 20. This is a simplest and potentially smallest embodiment of the present invention. The multitool 12 has a plier head 22 and first and second handles 18 and 20. The plier head 22 has opposing first and second plier parts 24 and 26 which pivot at 46 to open and close when the multitool 12 is in an open position. Each of the first and second handles 18 and 20 extend from the first and second plier halves 24 and 26 at 28. A tool shaft 14 is disposed on the handle 20 opposite the pivot at 28 at a pivot at 34. The tool shaft 14 extends outward of the pivot at 34 and stows into the outer side of the handle 20. The tool shaft 14 has a mating profile 80 which engages a complimentary mating profile 48 disposed on the pivot at 32 and locks the tool shaft 14 by closing the two handles 18 and 20 with the tool shaft 14. The tool shaft 14 is positioned and extends from a center of the two handles 18 and 20 when closed.

FIG. 3 shows a side view of a multitool 12 with locking multipurpose driver 14 in a closed position with all internal components from the closed position outlined. FIG. 4 shows an outer side view of the embodiment depicted in FIG. 3. The multitool 12 with locking multipurpose driver shaft 14 has a plier head 22. The plier head 22 has opposing plier halves 24 and 26. Each plier half 24 or 26 has a central pivot at 46 and with each handle at 28 as shown. The opposing plier halves are pivotable at 46 attached by a fastener (such as shown in FIGS. 24A, 24B, 34A and 34B) between the first and second ends at 28 of each half 24 or 26 of the plier head 22. FIG. 5 shows a side view of the embodiment depicted in FIG. 3 with the pliers 22 in the open position. FIG. 6 is a side view of the embodiment depicted in FIG. 3 in which the tool 50 is extended and the handles 18 and 20 are in the closed position. First and second handles 18 and 20 are attached to the pliers halves 24 and 26. Each of the handles 18 and 20 has a first end at pivot 28 and a second end at pivots 32 and 34. The first end pivots at 28 of each handle 18 and 20 is pivotably attached at the second ends at 28 of each plier half 24 and 26. FIG. 4 shows a side view with driver engaged and locked.

FIGS. 7A and 7B show side views of a multitool 12 depicting an alternative embodiment of the present invention which has more than one accessory tool 50 each of which has the same complimentary mating profiles 48 with FIG. 7B shows the internal position of the tool parts when stowed. FIG. 8 shows the multitool 12 of FIGS. 7A and 7B with the tool shaft 14 fully extended and profile 48 mated with the complimentary profile 48 of a tool accessory 50 with the handle lock mechanism 30 partially deployed.

FIGS. 9A-9C show another alternative embodiment of a multitool 12 showing an alternative mating profile 80 (fully extended position) and 82 (angle position) on the base 42. FIG. 9B depicts the tool shaft at an angle so the handle can be used for added torque, and FIG. 9C depicts to tool shaft in the fully extended position. In the stowed position, the plier head 22 can be seen off centered by the pin shaft 44 that holds the plier head 22 in position allowing the extra bit holder 54 be used.

FIGS. 10A-10E depict various views of the handles 18 and 20 from the edges and the top. FIG. 10A showing the

handle 20 with the tool shaft 14 and bit 16 stowed with the handle lock 30 fully open in the stowed position. FIG. B shows the accessory tool 50 lock 36 and rivet 40 with the bar 52 that engages the complimentary mating profile 48 when a tool 50 is extended. FIG. 10C shows an end without handle lock 30, FIG. 10D shows the end with the tool shaft 14 deployed. FIG. 10 E shows the end with the tool shaft 14 stowed and the handle lock 30 in the open position. FIG. 11 shows the other side of the handles to those depicted in FIGS. 10A-10E, in which more than one tool 50 is stowed in the handle 18 and showing the tool shaft 14 stowed. FIG. 12 is an exploded view showing the tool shaft 14 with the base 42 and bit 16 with the complimentary mating 48 of a tool accessory 50.

A locking mechanism 30 may be provided to hold the two handles 18 and 20 together, preventing the unintentional opening of the handles 18 and 20 from the closed position. The locking mechanism 30 is pivotably attached to the second end at 34 of the handle 20, and rotates to capture the extended shoulders of the fastener at 32 in the second of the opposing handle 18.

FIG. 13A-13D show side views of an alternative embodiment of a multitool 12 of the present invention showing differing position of the handle locking mechanism 30 going from the stowed position in FIG. 13A, to partially deployed positions in FIGS. 13 B and 13C, to all the way deployed and locked at pivot 32. Once the handle locking mechanism 30 is in place and the tool shaft 14 fulling extended, the multitool 12 becomes rigid and the tool shaft 14 cannot be moved. This is a safety feature as well as convenient. It can also be seen that the tool shaft 14 extends from the middle of the handles 18 and 20.

The locking mechanism 30 may possess a crossmember that spans the tool shaft 14, such that the tool shaft 14 carries the locking mechanism 30 via the interference of the tool shaft 14 and the crossmember of the locking mechanism 30 when the driver component base 42 and tool shaft 14 are rotated. Thus, the locking mechanism 30 may be rotated 180 degrees by deploying the driver component 42 and tool shaft 14, requiring only approximately 90 degrees further rotation in order to engage the extended shoulders of the fastener at 32 in the opposite handle 18.

FIG. 14 shows a side view of a multitool 12 according to alternative embodiments of the present design depicting the parts in open display. FIGS. 15A-15C show alternative accessory tools 50 with complimentary mating profiles 48. FIG. 15A shows a large flat screwdriver accessory tool 50. FIG. 15B shows an awl accessory tool 50. FIG. 15B shows a bottle opener accessory tool 50.

FIG. 16A-16F show an alternative view of a tool shaft base 42. The base 42 has an alternative profile and is shown from different angles demonstrating the interaction with the complimentary mating profile 48 of tool accessory 50. The tool shaft base 42 fits the tool shaft 14. FIGS. 17A-17E show alternative profiles of a tool shaft 14 used, with square (FIGS. 17B and 17C) and hexagonal (FIGS. 17A and 17D) alternative options depicted. The tool shaft 14 for example may mate with a hexagonal tool bit 16 and with a square profile of a driver component base 42, and vice versa. Conventional tool bits 16 may be used, and include tool bits 16 with two flat screwdrivers and with one flat and one Phillips screwdrivers. The screwdriver bits 16 shown have ball detent for use with detents 58 on the tool shaft 14 and tool bit holder 54.

FIGS. 18A-18E depict different perspectives of a bit holder 54 that may be incorporated into a handle (18 or 20) to store additional bits 16 for the tool shaft 14. The bit

storage component holder 54 has a shape which closely accepts the tool bit 16, while a hole or indentation 58 accepts the ball detente of the bit 16. This interaction secures the bit 16, while also allowing the bit 16 to pivot about its ball detente for ease of access and removal.

FIGS. 19A-19D show the handle locking mechanism 30 from various angles. FIGS. 20A-20I shows various parts of the multitool 12 of the present invention including the tool shaft 14 (FIG. 20A), tool bit (FIG. 20B), spare tool bit (FIG. 20C), handle lock 30 (FIG. 20D), plier head 22 (FIG. 20E), handles 18 and 20 (FIG. 20F), tool lock lever 36 (FIG. 20G), rivet 40 (FIG. 20H), and tool lock lever spring 56 (FIG. 20I). FIGS. 21A-21C shows front side and back views of a tool lock lever 36 with a mating bar 52 and a pivot 38. FIGS. 22A-22C show the operation of the tool lock lever 36 as it operates with a tool 50 that has a complimentary mating profile 48 that can be used to mate with the mating bar 52 of the tool lock lever 36 with the spring 56 and rivet 40 operating to release the tool lock lever 36 and free the tool accessory 50 to be stowed.

FIGS. 23A-23D show details of the handles 18 and 20 of an alternative embodiment of the multitool 12 according to the present invention. FIG. 24A-24C show an alternative embodiment for the pivots 28, 32, and 34 of the present invention including threaded pin 62, pin shaft 60, threaded pin 62 and pin shaft 60 heads 66 and 68, and spacer sleeve 64.

FIG. 25 shows another embodiment of the present design with the tool accessory locking mechanism 36 being disposed on the inside of the handle 18 in which the back profile of the bar 52 mates with the tool shaft 14 base 42. FIGS. 26A and 26B show an alternative configuration of the tool shaft base 42 and angle deployment mating profile 82 which permits the use of the drive shaft 12 fixed at an angle to the handles 18 and 20 and the handle locking mechanism 30 fully engaged in the lock position. FIGS. 27A and 27B show the alternative configuration of FIGS. 26A and 26B in which the tool shaft 14 is depicted in the fully extended position. FIG. 28 shows an embodiment of the multitool 12 with a tool accessory lock 36 on the inside of the handle 18 and the alternative design of the tool accessory 50 complimentary mating profile 48 with the tool accessory 50 fully deployed with the handles 18 and 20 in a closed position. FIGS. 29A and 29B show alternative tool accessories 50 that have the complimentary mating profile 48 for the embodiment of the multitool 12 in which the tool accessory lever lock 36 is on the inside of the handle 18. FIGS. 30A-30C shows the handles 18 and 20 of the multitool 12 according to the alternative embodiments depicted in FIGS. 25-29B. FIG. 31 shows an alternative of the tool shaft 12 base 42 which has two positions for mating profile at 80 and 82, and also shows the thumb ridges 84 which facilitate easy opening of the tools, and the detent 58 to facilitate mating with a shaft tool 14 that has a ball.

FIG. 32 shows an alternative embodiment of the present invention of a multitool 12 which has additional tools 74 disposed adjacent the plier head 22 at pivots 28. FIGS. 33A-33D show an alternative configuration of the handles 18 and 20 according to the embodiment of the multitool 12 depicted in FIG. 32 showing where the extra tools 74 are disposed. FIGS. 34A-34C show alternative threaded pins 62, pin shafts 60, and heads 68.

Additional alternatives are available. FIGS. 35A and 35B show alternative mating profiles 80, 82 and complimentary mating profiles 48 that provide for an angled position and an extended position accordingly. FIGS. 36A-36C show another alternative for the base 42 having a pin 86 and

11

groove 88 configuration which restricts the movement of the tool shaft 14 relative to the handle 20. FIGS. 37A-37C show an alternative bit holder 54 and detent 58 to receive a bit 16.

It is to be understood that the present invention is not limited to the embodiments described above, but encompasses any and all embodiments within the scope of the following claims.

The invention claimed is:

1. A multitool (12) with locking multipurpose driver, the multitool (12) comprising:

a plier head (22) and first and second handles (18 and 20); the plier head (22) having opposing first and second plier halves (24 and 26) which pivot at a central pivot (46) to open and close when the multitool (12) is in an open position;

each of the first and second handles (18 and 20) extend from the first and second plier halves (24 and 26) at plier-to-handle pivots (28);

a tool shaft (14) is disposed on the second handle (20) at a handle-to-tool shaft pivot (34) disposed on the second handle (20) opposite the plier head (22), wherein the tool shaft (14) extends outward of the handle-to-

tool shaft pivot (34), and

stows into the outer side of the second handle (20);

wherein the tool shaft (14) has a mating profile (80) which engages a complimentary mating profile (48) formed at an opposing pivot (32) on the first handle (18) opposite the plier head (22) and locks the tool shaft (14) by closing the first and second handles (18 and 20) with the tool shaft (14); and

the tool shaft (14) is positioned and extends from a center of the first and second handles (18 and 20) when closed.

2. The multitool of claim 1, wherein:

a mechanism for locking accessories in place operated by closing the first and second handles comprises a first indenture or tab at the base of the accessory which mates with a corresponding feature in the opposing first or second handle or on an accessory disposed in the opposing first or second handle with the tool shaft (14) disposed and extending from the center of the first and second handles (18 and 20).

3. The multitool of claim 2, further comprising: the mechanism for locking accessories in place operated by closing the first and second handles further comprises a second indenture or tab at an angle to the first indenture or tab which mates with a corresponding feature in the opposing first or second handle or on an accessory disposed in the opposing first or second handle to hold the tool shaft (14) at a different angle to the first and second handles (18 and 20) in order to apply more torque on the tool shaft (14).

4. The multitool of claim 3, wherein:

the safety handle locking mechanism (30) is partially/initially deployed by moving the tool shaft (14) into an open fully extended position.

5. The multitool with locking multipurpose driver of claim 1, further comprising:

a safety handle locking mechanism (30) that fits over both first and second handles (18 and 20) when closed.

6. The multitool of claim 5, further comprising a tool bit holder (54).

7. The multitool of claim 1, wherein the centrally disposed tool is a driver, and a tool shaft.

8. The multitool of claim 1, wherein the tool may be disposed in one of two open positions fully opened, and halfway opened.

12

9. The multitool 12 of claim 1, further comprising a thumb actuated safety lock (30).

10. The multitool 12 of claim 1, further comprising: a plier stop (44) disposed in the second handle (20) to position the plier head (22) off-center in the first handle (18).

11. A multitool 12 with locking multipurpose driver, the multitool (12) comprising:

a plier head (22) and first and second handles (18 and 20); the plier head (22) having opposing first and second plier halves (24 and 26) which pivot at a central pivot (46) to open and close when the multitool (12) is in an open position;

each of the first and second handles (18 and 20) extend from the first and second plier halves (24 and 26) at plier-to-handle pivots (28);

a tool shaft (14) is disposed on the second handle (20) at a handle-to-tool shaft pivot (34) disposed on the second handle (20) opposite the plier head (22), wherein the tool shaft (14) extends outward of the handle-to-

tool shaft pivot (34), and

stows into the outer side of the handle (20);

wherein the tool shaft (14) has a mating profile (80) which engages a complimentary mating profile (48) formed at an opposing pivot (32) on the first handle (10) opposite the plier head (22) and locks the tool shaft (14) by closing the first and second handles (18 and 20) with the tool shaft (14); and

the tool shaft (14) is positioned and extends from a center of the first and second handles (18 and 20) when closed; wherein the centrally disposed tool is a driver having a tool shaft.

12. The multitool of claim 11, wherein:

a mechanism for locking accessories in place operated by closing the first and second handles comprises a first indenture or tab at the base of the accessory which mates with a corresponding feature in the opposing first or second handle or on an accessory disposed in the opposing first or second handle with the tool shaft (14) disposed and extending from the center of the first and second handles (18 and 20).

13. The multitool of claim 11, further comprising: a mechanism for locking accessories in place operated by closing the first and second handles further comprises a second indenture or tab at an angle to the first indenture or tab which mates with a corresponding feature in the opposing first or second handle or on an accessory disposed in the opposing first or second handle to hold the tool shaft (14) at a different angle to the first and second handles (18 and 20) in order to apply more torque on the tool shaft (14).

14. The multitool with locking multipurpose driver of claim 11, further comprising:

a safety handle locking mechanism (30) that fits over both first and second handles (18 and 20) when closed.

15. The multitool 12 of claim 14, wherein: the safety handle locking mechanism (30) is partially/initially deployed by moving the tool shaft (14) into an open fully extended position.

16. The multitool of claim 14, further comprising a tool bit holder (54).

17. The multitool of claim 11, wherein the tool may be disposed in one of two open positions fully opened and halfway opened.

18. The multitool 12 of claim 11, further comprising a thumb actuated safety lock (30).

19. The multitool **12** of claim **11**, further comprising:
a plier stop **(44)** disposed in the second handle **(20)** to
position the plier head **(22)** off-center in the first handle
(18).
